Design for Printing Types.

UNITED STATES PATENT OFFICE.

JAMES M. CONNER, OF NEW YORK, N. Y.

DESIGN FOR PRINTING-TYPES.

Specification forming part of Design No. 6,574, dated April 8, 1873; application filed March 15, 1873.

To all whom it may concern:

Be it known that I, JAMES MADISON CONNER, of the city and county of New York and State of New York, have originated and designed a new Pattern for Printing-Types, which I call Inclined Antique, reference being had to annexed printed impressions thereof. It differs from every other kind of type in style, shape, and proportion.

What I claim as my invention, and desire to secure by Letters Patent, is—

The design or pattern for printing-types herein set forth.

JAMES M. CONNER.
